(57) **CLAIM**

The ornamental design for a splice coupler as shown and described.

DESCRIPTION

FIG. 1 is a front top perspective view of a splice coupler showing my new design in accordance with one embodiment;

FIG. 2 is a rear bottom perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof; and,

FIG. 8 is a left side elevation view thereof.

The broken dash-dot lines shown in the figures are for the purpose of illustrating non-claimed portions and form no part of the claimed design. Neither the portions shown in broken dash-dot lines, nor the broken dash-dot lines themselves form any part of the claimed design.

The broken dash lines shown in the figures are for the purpose of defining the bounds of the claimed design. The broken dash lines themselves form no part of the claimed design.
